UNITED STATES PATENT OFFICE.

EMIL J. JONES, OF JAMESTOWN, NEW YORK.

KNOCKDOWN SHEET-METAL DRAWER.

1,352,002.

Specification of Letters Patent. Patented Sept. 7, 1920.

Application filed April 26, 1920. Serial No. 376,623.

To all whom it may concern:

Be it known that I, EMIL J. JONES, a citizen of the United States, residing at the city of Jamestown, in the county of Chautauqua and State of New York, have invented certain new and useful Improvements in Knock-Down Sheet-Metal Drawers, of which the following, taken in connection with the accompanying drawings, is a specification.

The invention relates to knock-down sheet metal drawers in which the parts are detachably attached to one another so that they may be shipped knocked-down and set up at their destination, or may be knocked-down for any other purpose, such as repair or storage; and the invention consists in providing a drawer having interlocking parts which engage one another so that all said parts will be fixedly held in attachment to one another by means of two attaching bolts and a spring catch, said parts being so constructed as to permit their being easily standardized for manufacture by means of machine dies and presses, thereby accomplishing said manufacture in an economical manner and giving great durability and strength to the set-up drawer; and the invention consists in the novel features and combinations hereinafter set forth and claimed.

In the drawings, Figure 1 is a perspective view of the assembled drawer showing certain of the features of its construction. Fig. 2 is a perspective view of the drawer parts separated from one another with lead lines showing the manner of assembling the same. Fig. 3 is a perspective view of the inner side of the rear plate of the drawer head showing the lock as slipped into the same and the locking lugs on each of the end flanges, also the locking slot in the bottom flange. Fig. 4 is a horizontal sectional view of the drawer side at line 4-4 in Fig. 5, the middle portion being broken away to show the front and rear ends of the drawer. Fig. 5 is a vertical sectional view of the front portion of the drawer at line 5-5 in Fig. 8. Fig. 6 is a detail perspective view of the lock holding bracket plate which is spot welded to the inner side of the rear plate of the drawer head so that the lock may be slipped into the same as shown in dotted outline. Fig. 7 is a vertical sectional view of the top portion of the drawer head showing

the lock in dotted outline. Fig. 8 is an elevation of the drawer with the front plate of the drawer head removed showing the rear head plate in position and a locking or latching spring on the bottom plate of the drawer extending up through the same to lock said rear plate of the drawer head in position when turned into the front plate of the drawer head as shown in Fig. 5 in dotted outline; and Fig. 9 is a perspective view of said locking spring.

Like characters of reference refer to corresponding parts in the several views.

The numeral 10 designates the drawer head, and the numerals 11 and 12 the drawer sides, 13 the drawer bottom, 14 the rear end and 15 the rear plate of the drawer head 10.

The drawer head 10 has the inturned spaced return bend flanges on all sides which form said drawer head into a box-shaped sheet metal head having the inturned lugs 16 with the slots 17 in each of said lugs at each end of said drawer head. The lugs 16 enter the holding slots 18 in the drawer sides 11 and 12, which slots 18 are preferably spaced from the forward end of the drawer sides so as to fit said forward end of the drawer sides against the inner wall of the drawer head 10.

The drawer bottom 13 has downwardly turned flanges 34 on each side which fit into the upwardly turned flanges 19 on the lower edges of the drawer sides 11 and 12. The drawer head 10 also has the upturned lugs 20 which engage in the spaced slots 21 in said drawer bottom 13, which slots 21 are also preferably spaced from the forward end of the drawer bottom 13 a sufficient distance to press said bottom against the inner wall of the drawer head 10 to brace the same.

The rear end plate 14 has rearwardly turned flanges on its lower edge and ends, the bottom flange engaging in the upwardly return bend flange 24 on the bottom plate 13 and the end flanges engaging in the return bend flanges 22 on the rear ends of the drawer sides 11 and 12, a bolt 23 being provided through suitable holes in the rear ends of the drawer sides 11 and 12 and through the end flanges on the rear end plate 14, thereby locking all the parts firmly at the rear end of the drawer.

The drawer parts are firmly locked in position at their front end by means of the rear plate 15 of the drawer head 10, which

rear plate 15 has forwardly turned flanges on all its sides, the end flanges having the locking lugs 25 which enter the slots 17 in the lugs 16 on the drawer head 10, thereby locking the drawer sides 11 and 12 onto said lugs and the drawer head 10.

The upper flange 26 is shaped to spring within the box-shaped upper flange of the drawer head or front 10 so that said rear plate 15 can be turned downwardly into place by first inserting said upper flange 26 within the box-shaped upper flange of the drawer head, said rear plate 15 turning on the line 27 as shown in Fig. 5. A leaf spring 28 is attached on the under side of the drawer bottom 13 and extends up through slot 32 in said drawer bottom to engage in the continuance of said slot 32 in the lower flange 33 of said rear plate 15 of the drawer head 10.

As the rear plate 15 swings into place, the lugs 25 are so spaced as to seek the slots 17 in the lugs 16 at each end of the drawer head, and the upper end of the spring 28 is inclined so as to snap into the slot 32 in the flange 33. At the same time, the tumbler of the lock 29 which is inserted into the open bracket plate 30 on the inner side of the plate 15 seeks the opening 37 provided in the front plate of the drawer head 10, said lock 29 having been slipped into position in the drawer bracket 30 before the rear plate 15 is inserted into the front plate of the drawer head. This arrangement of the lock 29 holds it firmly in position.

The front plate of the drawer head is preferably made with an inner plate 36 which is held in place by the nuts 38 on the inner ends of the handle 31, a sheet of asbestos 35 being placed between the inner wall of the front plate of the drawer head 10 and said inner plate 36. Around the opening 37 for the tumbler of the lock 29, a spacing plate 39 is preferably provided so as to strengthen the parts at this point and to hold the sheet metal plates and the lock 29 firmly in line.

The manner of assembling the set-up drawer as shown in Fig. 1 has been given in the description thus far. In order to disassemble or knock down the drawer, the bolts 23 are withdrawn, thereby permitting the withdrawal of the rear end plate 14. A tool is then inserted in the downward curve of the leaf spring 28, thereby pressing said leaf spring downward sufficiently to permit the rear plate 15 being moved rearwardly on the radial arc 27 and removed from the drawer, after which the bottom 13 and sides 11 and 12 may be easily removed from the front plate of the drawer head 10.

It is apparent that all of said sheet metal plates or parts can be easily struck-up by means of suitable dies so that the drawer can be economically manufactured and also

when assembled, the parts of said drawer are pressed and locked firmly in position, making a strong and durable construction.

I claim as new:

1. In a drawer, a front plate having in-turned end and top and bottom flanges, spaced lugs on each of said end flanges having slots therein and spaced lugs on said bottom flange, drawer side plates and a bottom plate having similarly spaced slots to receive said lugs therethrough, a rear plate for the drawer head having locking lugs spaced to enter said slots in said end lugs to hold said part firmly in position, and a rear end plate for said drawer.

2. In a knock-down sheet metal drawer, a box-shaped drawer head having a removable rear head plate with a forwardly extending flange on its lower edge, said flange having a slot therethrough, a drawer body connected to said drawer head having a bottom with a slot therethrough registering with said slot in said rear head plate when in the assembled position, a leaf spring catch on said drawer body having a downward and upward bent end portion to engage through said registering slots and hold said rear head plate and drawer body in position, said downwardly and upwardly bent portion permitting the insertion of a tool therein to removably disengage said spring from said registering slots and disassemble said parts.

3. In a drawer, a front having its four edge portions bent inwardly and rearwardly to form a box-shaped front plate by said rearward and inward flanges, inwardly extending spaced lugs on said end and bottom flanges of said front plate, said inwardly extending lugs on said end flanges having slots therein, drawer sides having spaced slots therein to engage said spaced lugs on said front plate, a drawer bottom having downwardly turned edges to engage in said upturned edges of the drawer sides, spaced slots engaging over the spaced lugs on the bottom flange of said front plate, a rear plate for the drawer head having its edges turned forwardly in flanges, the end flanges having spaced lugs fitting in the spaced slots in said front plate, a spring on the under side of said bottom plate engaging through a suitable opening in said bottom plate and the bottom flange of said rear plate of the drawer head, a rear end plate having rearwardly turned flanges to engage in the oppositely turned bent flanges on the drawer sides and bottom, and bolts through said rear flanges and drawer sides to lock the parts firmly in position.

4. In a drawer, a head, a bottom, a removable plate, interengaging means between the plate and the top of the head, and a spring catch for connecting the bottom of the plate to the bottom, said catch having a part ex-

tending below the bottom so as to allow same to be engaged and moved out of engagement with the plate.

5. In a drawer, a head, a removable plate therefor, a bottom, means to removably connect the top part of the plate to the head, and a displaceable latch arranged between the head and plate to hold the bottom of the plate in position, said latch having a part 10 accessible from below the bottom to enable displacement thereof and thereby removal of the plate.

6. In a drawer, a head, a removable plate therefor, a bottom, means to removably connect the top part of the plate to the head, said plate having a part overlying the bottom, and means extending through the bottom and said part of the plate and accessible 15 from below the bottom for removably securing the plate in position.

7. In a drawer, a head, a removable plate therefor, a bottom, means to removably connect the top part of the plate to the head, and means accessible from below the bottom 20 for removably securing the plate in position.

8. In a drawer, a head, a removable plate therefor, a body, means to removably connect the plate at its top part to the top part of the head, and withdrawable means between the body and the lower part of the 30 plate to hold the latter in place, said means being accessible exteriorly of the body so as to be withdrawn to allow of removal of the plate.

9. In a drawer, a front plate having in- 35 turned end and top and bottom flanges, spaced lugs on each of said end flanges having slots therein, drawer side plates having similarly spaced slots to receive said lugs therethrough, a rear plate for the drawer 40 head having locking lugs spaced to enter said slots in said end lugs to hold said part firmly in position, and a bottom and a rear end plate for the drawer.

In testimony whereof I have affixed my 45 signature in the presence of two witnesses.

EMIL J. JONES.
